UNITED STATES PATENT OFFICE.

ARNOLD J. TANNER, OF NORTH HAVEN, CONNECTICUT.

DISPLAY CONTAINER.

Application filed August 20, 1927. Serial No. 214,271.

The present invention relates to containers useful for displaying and dispensing merchandise, and the chief object of the invention is to provide a serviceable, simple and 5 economically constructed container which can be easily assembled for packing and set up for displaying the contents.

The present invention is an improvement in the type of container which forms the 10 subject matter of a co-pending application Serial No. 174,743, filed March 12, 1927. In the previously proposed construction, the container consists of a receptacle having an open top and front and a separate member 15 which may be utilized either as a closure means for the open front and a display card by changing the position of the same relatively to the receptacle part of the container. Also, in the previously proposed container, 20 the receptacle of the container is formed from a blank which has the ends thereof glued together.

The present invention introduces novel features, amongst other, one being the design 25 of the blank which can be assembled without gluing to form the receptacle, and further the separate display and cover member is designed to operate as a closure means for both the open front and open top of the 30 container besides serving as an advertising or display card.

As applied to one embodiment of the invention the several novel features thereof will be hereinafter fully described with reference to the accompanying drawings, wherein:

Figure 1 is a perspective view showing the box filled and set up in position to display the contents;

Figure 2 is a perspective view showing a box packed and closed ready for shipping;

Figure 3 is a perspective view showing the back of the container;

Figure 4 illustrates the blank from which 45 the container is constructed, and

Figure 5 illustrates the blank from which the closing cover and advertising or display card is constructed.

Referring to said drawings, more particularly to Figure 4, wherein the complete blank is shown. This blank is changed according to the dimensions and shape of the container to be constructed, and in every instance the blank should be so designed that 55 a number of similar blanks can be cut out with economy. This blank is divided into

a number of substantially parallel sections vertically arranged relatively to each other and defined by creases or folding lines. The various sections are designated by different 60 reference numerals, and the same sections in the set up figures are similarly numbered so that each piece or section can be readily identified. The blank is divided into the following sections; 1, is the central section 65 which constitutes the front of the box, 2 are intermediate sections forming the sides of the container, 3 and 4 are the end sections which when joined together form the back 70 of the container, 5 is an extension from the end section 3 and this extension serves, when folded inwardly, as a lining for the back wall of the container whereby the same is considerably reenforced. The lower and upper edges respectively of the end sections 75 3 and 4 are oblique so that the union of the two sections together is diagonally across the back of the container. The section 3 is provided with an elongated slot 6 and the section 4 has an engaging tongue 7 80 projecting at right angles to the edge of the section.

The receptacle of the container is formed by folding the different sections on the vertical cross lines 8. To unite the two sections 85 together the tongue 7 is inserted into the slot 6, and to insure rigidity and retention against accidental release the tongue is folded inwardly on the line 9, and the section 4 preferably over-laps the section 3. 90

The receptacle is partly formed when the blank is folded as above and to close the bottom of the container the tongues or flaps 10, 11, 12 and 13 which depend from the several sections, are folded inwardly, one 95 over the other. The tongues 11 and 13 are first folded and then the flap 10 is folded. The latter flap has the slot 14 in which the tongue 15 of flap 12 is engaged, and in this case, as before this tongue 15 is folded on the line 16 so as to hold the tongue against accidental release. It will be noted access is had to the tongue 15 from the interior 100 through the opening 17 into the front of the container, therefore, to fold the tongue 15 over it is only necessary to lift the tongues 11 and 13 to gain access to said tongue 15, and when the tongues 11 and 13 are back in place these tongues aided by the weight 105 of the contents of the container securely hold the bottom of the container in the closed position. 110

Figure 5 illustrates the blank which is employed to form the cover and display card of the container. This blank has the portion 18, intermediate portion 19 and end portion 20. To employ this blank as a cover for the container, it is folded on the creased line 21 and the portion 19 forms the cover for the open top of the container and portion 18 slides into the open front of the container behind the side pieces 22. To retain the cover in place, the end 20 is inserted back of the contents of the container against the lining 5, or if the latter should be dispensed with, directly against the back wall 15 of the container. The cover when so placed may be sealed by suitable seals 23 and the container is then completely ready for shipment. When the dealer opens the container, he need only tear the seals, bodily remove 20 the cover and fold the same on line 21. One of the bottom corners of the cover member when so doubled, is inserted into the slot 24 and the other bottom corner is inserted behind the over-lapping edge of the section 25 4 whereby the cover is effectually held in a rigid upright position with the front surface of the section 18 of the cover member fully exposed.

The blank for the container is constructed 30 of one piece and printing is only required on one side thereof. The folding lining 5 is desirable because besides reinforcing the back of the container it also presents a finished surface to the back of the container 35 when the contents are partially removed. Further, the folding lining helps to provide a firm support for the cover when the latter is used as a display or advertising medium.

The invention hereinbefore described has 40 many advantages, and one in particular is that by arranging the union of the blank together by diagonally disposed retentive means at the back of the container, the required stock is left to connect and support 45 the tuck-in or folding flaps which close and reinforce the bottom and back wall of the container and which feature is applicable to various types of containers. It is to be understood that any modified application of 50 the invention and any other modification coming fairly within the terms of the appended claims shall be covered thereby.

I claim—

1. A container composed of a blank having 55 a plurality of end and intermediate sections defined by folding lines; said sec-

tions having depending flaps or tongues forming the bottom of the container; one of said sections having a cut away portion to provide an open front for the container; a 60 separate member adapted to form a cover for the open top and front of the container; and said sections being united by interlocking means which in conjunction with an additional slot serves also as a means for supporting said separate member in an upright position to operate as a display card. 65

2. A container as described and a cover therefor, said container being composed of a blank divided by scoring to define a central, intermediate and end sections forming respectively the front, sides and back of said container; folding flaps and tongues extending from said sections forming closure means for the bottom of the container; said central section being partly cut out to provide an open front for the container; said cover being composed of a separate blank arranged to fold and to be held in a position so as to provide a retaining flap and closure means for the open top and front of the container or to operate as a display medium for the container and one of said end sections having an extension therefrom arranged to fold into the container to form 80 a back lining therefor. 70

3. A container as described and a cover therefor, said container being composed of a blank divided by scoring to define a central, intermediate and end sections forming respectively the front, sides and back of said container; folding flaps and tongues extending from said sections forming closure means for the bottom of the container, said central section being partly cut out to provide an open front for the container; said cover being composed of a separate blank arranged to fold and to be held in a position so as to provide a retaining flap and closure means for the open top and front of the 90 container or to operate as a display medium for the container, one of said end sections having its upper edge diagonally disposed, the lower edge of the other end section being similarly disposed and interlocking 95 means arranged in alignment relatively to said edges for uniting said sections together. 100

Signed at New Haven, county of New Haven, State of Connecticut, this 19th day of August, 1927.

ARNOLD J. TANNER.
